UNITED STATES PATENT OFFICE.

E. F. LEWIS FRITZ, OF CHICAGO, ILLINOIS.

RIFLE.

Application filed September 30, 1922. Serial No. 591,626.

To all whom it may concern:

Be it known that I, E. F. LEWIS FRITZ, a citizen of the United States, and a resident of the city of Chicago, county of Cook, and 5 State of Illinois, have invented certain new and useful Improvements in Rifles, of which the following is a specification.

My invention relates to novel improvements in rifles and has for its principal object 10 the provision for automatically feeding cartridges to the firing barrel of the rifle, the provision being of such construction which will be highly efficient in use and economical in manufacture.

15 Among the salient objects of the invention is the provision for actuating the automatic feed upon manipulating the trigger mechanism embodied in a rifle of the usual construction such as the Remington No. 8 or the 20 Winchester rifle. In this connection it is intended that the mechanism embodied in the invention be associated with a rifle provided with an automatic concussion reload of a construction similarly now in use in the 25 rifles above mentioned.

Other objects will appear hereinafter.

The invention consists in the combinations and arrangements of parts hereinafter described and claimed.

30 The invention will be best understood by reference to the accompanying drawings forming a part of this specification, and in which,

Fig. 1, is a side elevational view of a rifle, 35 partly in section, embodying the invention and taken substantially on line 1—1 of Fig. 2;

Fig. 2, is a sectional detail view of the same, taken substantially on line 2—2 of

40 Fig. 1;

Fig. 3, is a sectional detail view of the same, taken substantially on line 3—3 of Fig. 1;

Fig. 4, is a detail view of the safety catch, 45 mechanism, embodied in the invention;

Fig. 5, is a sectional detail view of the rifle embodied in the invention, and taken substantially on line 5—5 of Fig. 2;

Fig. 6, is a sectional detail view of the 50 same taken substantially on line 6—6 of Fig. 5, and

Fig. 7, is a fragmentary sectional detail view of the same, taken substantially on line 7—7 of Fig. 1.

In carrying the objects of the invention 55 into effect and with reference to the drawings, 10 indicates the breech provided with automatic concussion reload mechanism (not shown) usually associated with a Remington or Winchester self-loading rifle, and 11 indicates the stock of the rifle which in this instance is provided with a magazine chamber 12 having a door opening 13 leading thereto, said door opening being closed by a spring controlled door 14 as best shown in 60 Fig. 6. Arranged in the magazine chamber 12 is a guide 15 (see Fig. 2) for the reception of the heads 16 of the cartridges 17 and is arranged and adapted to guide the cartridges during their travel to the automatic 65 feed mechanism (not shown) arranged in the breech 10.

Associated with the stock 11 are pulleys 18, 19 and 20 over which a guide cable 21 is 70 adapted to pass. Associated with the guide cable 21 is a push plate 22 (see Fig. 5) forward movement of which is imparted through the medium of a spring member 23, said push plate when in the position illustrated in Fig. 5 is received by a housing 24. 75 The push plate 22 is provided with a lateral projection 26 which is fixed to the cable 21 by any suitable means, the arrangement of which being such that upon movement of the cable 21 movement will be imparted to 80 the push plate 22 which in turn forces the cartridges 17 in a direction toward the concussion actuated carriage (not shown).

85 The pulley 20 is mounted on a stud shaft 27 which carries a gear 28 meshing with a gear 29 carried on a stud shaft 30. On the shaft 30 is arranged a ratchet wheel 31 for engagement with a spring controlled dog 32 pivotally carried by the trigger 33 as 90 shown in Fig. 1. This construction is such that upon movement of the trigger 33 the dog will engage one of the teeth of the ratchet wheel 31, imparting movement to the shaft 30, which through the movement of the gears 28 and 29 imparts movement to 95 the shaft 27 causing the cable 21 to travel in the direction indicated by the arrow 100

shown in Fig. 1. It will be thus seen that upon each operation of the trigger 33 the push plate 22 will be caused to force the cartridges into firing position.

5 In the present invention I provide a safety lock device which comprises two oppositely disposed spring controlled pawls 34 and 35 adapted for engagement with the teeth of the gear 28, said pawls being carried by a 10 plate 36 fixed on a stud shaft 37 provided with an operating handle 38, through the medium of which the pawls 34 and 35 are alternately brought into engagement with the gear 28. The operating handle 38 is 15 located on the left hand side of the stock 11 and is held in its receptive position through the medium of spring levers 39. When the pawl 34 is in engagement with the teeth of the gear 28 the cable 21 is permitted to rotate in one direction only and when the pawl 34 is forced out of engagement and the pawl 35 forced into engagement with the gear 28 the cable is permitted to rotate in the opposite direction and when both the pawls 20 are out of engagement with the teeth of the gear 28 the cable is permitted to rotate in either direction.

When the cartridges have become exhausted and the push plate is in its extreme 30 forward position, and it is desired to draw the push plate back to its initial position, or rearmost position, by manipulating the handle 40 carried on shaft 41 carrying the pulley 18, the cable 21 will be caused to 35 draw the push plate 22 back to its initial position. Before this operation of the cable can be accomplished, it is necessary to release the dog 32 from engagement with the ratchet wheel 31 and this is accomplished 40 by manipulating a pin 31' fastened through slot 32' formed in the left hand side of the stock 11.

The cartridges are fed into the guide 15 through the door opening 13 and through 45 the medium of the trigger mechanism 32 and push plate 22, to a position to be received by the concussion actuated means, and after the cartridges have been exploded, they are discharged by means of the concussion actuated carriage, herein alluded to. The concussion actuated carriage is not disclosed in the drawings for it is to be understood that the embodiment of my invention 50 can be used on any rifle provided with concussion actuated carriage discharge means.

In the present invention I provide means for storing a large reserve of cartridges which can be readily brought automatically into firing position and which can be manufactured at a nominal cost and associated 60 with any type of rifle similar to a rifle herein referred to.

While I have illustrated and described my preferred form of construction for carrying 65 my invention into effect, this is capable of

variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. In a rifle, the combination with the stock thereof, a storage compartment in the stock adapted to hold a number of cartridges, a member adapted for movement within the compartment and actuated by the trigger mechanism of the rifle, for feeding the cartridges into a firing position, and means for locking the member against movement in one direction but permitting movement of the member in the opposite direction. 80

2. In a rifle, the combination with the trigger mechanism and the stock thereof, of a storage compartment in said stock; a cable arranged in said compartment; a push plate associated with said cable and means actuated by the trigger mechanism for operating said push plate; and safety means to prevent operation of said push plate. 90

3. In a rifle, the combination with the trigger mechanism and stock thereof, of a storage compartment in said stock; pulleys arranged in said storage compartment; a guide cable associated with said pulleys and actuated by the trigger mechanism of said rifle; and a push plate associated with said cable adapted to feed cartridges arranged in said storage compartment to firing position in said rifle. 100

4. In a rifle, the combination with the trigger mechanism and stock thereof, of a storage compartment in said stock; a guide arranged in said compartment for the reception of the heads of a number of cartridges; pulleys arranged in said storage compartment; a guide cable associated with said pulleys and actuated by the trigger mechanism of said rifle; and a push plate associated with said cable adapted to feed said cartridges arranged in said storage compartment to firing position in said rifle. 110

5. In a rifle, the combination with the trigger mechanism and stock thereof, of a storage compartment in said stock; pulleys arranged in said storage compartment; a guide cable associated with said pulleys and actuated by the trigger mechanism of said rifle; a push plate associated with said cable adapted to feed cartridges arranged in said storage compartment to firing position in said rifle; and means for returning said push plate to its initial position. 120

6. In a rifle, the combination with the trigger mechanism and stock thereof, of a storage compartment in said stock; a guide arranged in said compartment for the re- 130

ception of the heads of a number of cartridges; pulleys arranged in said storage compartment; a guide cable associated with said pulleys and actuated by the trigger mechanism of said rifle; a push plate associated with said cable adapted to feed said cartridges arranged in said storage compartment to firing position in said rifle; and

means for returning said push plate to its initial position.

In testimony whereof I have signed my name to this specification in the presence of a subscribing witness.

E. F. LEWIS FRITZ.
